W. L. LAIB

SUPPORT FOR LAMPS

Filed April 12, 1926

Inventor:
William L. Laib
By Harry J. Bomer
Fifty.

UNITED STATES PATENT OFFICE.

WILLIAM L. LAIB, OF OAK PARK, ILLINOIS.

SUPPORT FOR LAMPS.

Application filed April 12, 1926 Serial No. 101,599.

This invention relates to devices for supporting and connecting lamp hoods and electric lamps, such as are capable of being used on or in connection with electric signs or the like, or for other or similar purposes.

The principal object of the invention is to provide a simple, economical and efficient device for supporting and connecting lamp hoods and lamps, and more particularly, to provide an improved device for supporting and connecting color hoods and electric lamps such as are adapted to be used on or to form a part of an electric sign, or for other or similar purposes.

A further object of the invention is to provide an improved means for supporting and connecting color hoods and electric lamps, whereby the electric lamps of or forming a part of an electric sign may be secured in position upon the sign board or plate, and the color hoods for covering such lamps may be removably mounted and detachably secured in position upon such hood-supporting means and removed therefrom with facility and without disturbing the lamps, and whereby the hood-supporting means may be secured upon the sign board or support and connected with the lamp by means of the lamp socket or lamp and in such a manner as to permit the removal of the hoods without disturbing or removing the lamps.

Other and further objects of the invention will appear from the following description and claims, and from an inspection of the accompanying drawings, which are made a part hereof.

The invention consists in the features, combinations, details of construction, and arrangement of parts herein described and claimed.

In the accompanying drawings—

Figure 1 is a view in section taken through the center of a lamp hood and hood-supporting device for an electric lamp on or forming a part of an electric sign, with parts of the lamp socket shown in section and other parts of the socket shown in elevation, and with the sign board or plate on which the hood and lamp are supported shown in section, all constructed in accordance with my invention;

Fig. 2 is a sectional view of the lamp and lamp hood and supporting and connecting means therefor, taken on line 2—2 of Fig. 1, looking in the direction indicated by the arrows, and showing the inner and outer annular hood-supporting members and the

overlapping or interlocking flanges for detachably connecting the same with the hood, the lamp and the sign board or plate;

Fig. 3 is a bottom plan view of the outer flanged hood-supporting member;

Fig. 4 is a top plan view in detail of the inner recessed and flanged socket-engaging member of the hood-supporting device; and

Fig. 5 is a detail bottom plan view of the inner and outer annular detachably connected flanged members of the hood-supporting device shown in said Figs. 1, 2, 3, and 4.

In constructing an improved device for supporting and connecting lamp hoods and electric lamps, and an improved electric sign provided therewith, I provide one or more lamp hoods or color hoods 1, formed, by preference, of colored glass, and each adapted to encircle and enclose a corresponding electric lamp bulb 2 which is provided with a metallic screw-threaded neck 3 adapted to be removably inserted in screw-threaded engagement with a similarly screw-threaded metallic sleeve or inner socket member 4 of 80 a lamp socket 5, said socket consisting of or comprising in its construction a bottom socket member or base 6 of porcelain or other suitable insulating material, an inner socket sleeve member 7 which is also formed of 85 porcelain or similar insulating material and provided with an inner screw-threaded bore or threaded surface portion 8 on a tapered annular neck or sleeve portion 9 which extends into a similarly tapered axial opening 90 10 in said bottom socket member or base 6 and between the sleeve 4 and said base 6, the screw-threaded bore 8 being in screw-threaded engagement with the inner threaded metallic sleeve 4 which is fixed to the base or 95 socket member 6 and in threaded engagement with the neck 3 of the lamp bulb. The lamp bulb 2 is, of course, provided with the usual incandescent filament 11 having the usual electric terminals—not shown—which are 100 adapted to be engaged by or electrically connected with corresponding poles or terminals 12 and 13, respectively, in the bottom socket member or insulating base 6, said terminals being adapted to be connected with an electric circuit and source of electric supply by means of wires 15, 16, or equivalent electrically conductive elements. (See Fig. 1.)

The glass lamp hood or color hood 1 has annular or circular side walls, and its rounded closed end 17 is adapted to cover and enclose the rounded end of the glass lamp bulb

2, the opposite or open end 18 of the hood 1 being provided with an outer screw-threaded rim or peripheral marginal portion 19, and having, by preference, an outer peripheral bead 20 at or near the upper extremity of the threaded portion 19, as shown in Fig. 1.

A metallic cup-shaped hood-supporting and connecting device 22 is provided, for 10 supporting the hood in its proper position with respect to the lamp or lamp bulb 2 and with respect to the sign board or plate 21 or other or similar support upon which said hood and lamp are to be mounted, and for 15 connecting the hood with the lamp or lamp bulb and socket and with the sign board or plate 21.

My improved hood-supporting and connecting device 22, consists of or comprises, 20 by preference, an outer annular metallic hood-engaging and supporting member 23 having an up-standing outer peripheral annular flange or main body portion 24, the upper extremity of which is provided with an inner-threaded portion 25 which is adapted to be detachably secured in engagement with the inner threaded portion 19 of the hood 1. The threaded portion 25 may be in the form 30 of either a continuous helical thread or in the form of a broken thread or one or more inwardly projecting bosses adapted to act in lieu of a thread for detachably engaging the thread 19 on the hood.

The outer annular metallic hood-engaging 35 and supporting member 23 is provided with a plurality of inwardly extending securing flanges 26, 26, which are formed on and turned inward with respect to the bottom rim or peripheral margin of said outer annular member 23, in position to detachably engage the adjacent face of the sign board or plate 21 to which said outer annular member 23 of the hood-supporting device 22 is to be secured.

The outer annular hood-engaging and supporting member 23 has an inwardly projecting bead 27 thereon which extends around the inside of the flange or wall 24 and is adjacent to but spaced apart with respect to the inner securing flanges 26, 26. An inner annular plate member 28 having a central opening therein for receiving the depending sleeve portion 9 of the inner socket sleeve 50 member 7, encircles said sleeve portion 9, and is detachably secured in position upon the support or sign board 21 by means of said socket sleeve member 7 which is provided with a downwardly-facing annular shoulder 55 29 that projects outward beyond the periphery of the part 9 of said sleeve 7 and is adapted to admit and clamp the inner bottom annular plate member 28 between said annular flange or shoulder 29 and the sign board or plate 21.

60 The inner or bottom annular plate 28 has a

plurality of peripheral recesses or notches 30, 30, which are adapted to admit or permit the insertion and removal of the securing flanges 26, 26 on the outer hood-engaging annular member 23 while said inner or bottom 70 annular plate 28 is securely held in position between the shoulder 29 of the inner socket sleeve member 7 and the sign board or plate 21. Segmental peripheral marginal portions or circumferential locking flanges 31, 31 on the inner 75 annular plate 28 are located between the peripheral recesses or notches 30, 30, and adapted to detachably engage and overlap or interlock with the inner flanges 26, 26 on the outer hood-engaging annular member 23, when said inner flanges 26, 26 are inserted in said recesses and turned by partially rotating the outer 80 annular member 23, so as to cause said parts or flanges 26 and 31 to overlap and engage or interlock. The outer annular hood-engaging member 23, with the hood 1 supported thereon, is thus adapted to be detachably secured to the inner recessed plate 28 which is securely held between the annular shoulder 29 of the socket sleeve 7 and the sign board 21 or other 85 similar or suitable support.

A gasket or washer 32 is interposed between the annular shoulder 29 on the inner socket sleeve member 7 and the face of the sign board or support 21, and serves to space the annular plate 28 apart from the sign board 21 a sufficient distance to permit the securing flanges 26, 26 on the outer annular member 23 to be inserted through the peripheral recesses 30, 30 in the part 28 and to pass between the 100 peripheral marginal portions or segmental peripheral locking flanges 31, 31 and the surface of the sign board, as the outer annular hood-engaging and supporting member 23 is partially rotated in the operation of securing 105 the part 23 to the inner annular plate 28.

From the foregoing it will be readily understood that the inner or bottom annular plate 28 is secured in position upon the sign board 21 by means of the socket members 6 110 and 7, and the inner metallic screw-threaded sleeve or socket member 4, which serves to detachably connect the socket members 6 and 7, and also to connect the bulb with the socket. The inner or bottom plate 28 being thus secured to the sign board or support 21 and detachably connected with the outer hood-engaging and supporting annular member 23 by means of the interlocking flanges 26, 26, and 31, 31, co-acts with the socket members 6, 7, 115 120 and 4, and with said outer hood-engaging and supporting member 23 to support and detachably secure and hold the hood in position, and to connect the hood with the lamp and with the sign board or support 21.

The sign board or lamp-supporting plate 21 is provided with and adapted to support any desired number of electric lamps and lamp hoods in proper relation to each other, for forming an electric sign.

I claim:

1. In a device of the class described, the combination of a glass lamp hood adapted to enclose a lamp bulb, an outer annular metallic hood-engaging member in supporting engagement with said hood, securing flanges on said metallic hood-engaging member, an inner annular plate having peripheral marginal portions adapted to detachably engage said securing flanges on said outer annular hood-engaging member, said inner annular plate having an opening therein for receiving a lamp socket, a lamp socket extending into said opening, a lamp-supporting plate interposed between said lamp socket and said inner annular plate and adapted to form a sign board of an electric sign, and securing means on said socket and in securing engagement with said inner annular plate, said securing means comprising a peripherally shouldered screw-threaded sleeve having screw-threaded connection with the lamp socket and extending through an opening in said lamp-supporting plate and through and in clamping engagement with said inner annular plate and adapted to secure said socket and said inner annular plate to opposite sides of said intermediate lamp-supporting plate.
2. In a device of the class described, the combination of a glass lamp hood adapted to enclose a lamp bulb, an outer annular metallic flanged hood-engaging member in supporting engagement with said hood, an inner annular metallic plate having peripheral marginal portions adapted to be detachably secured in locking overlapping engagement with adjacent flanged portions of said outer annular flanged hood-engaging member, said inner annular plate having an opening therein for receiving a lamp socket, a lamp socket having a screw-threaded metallic sleeve portion extending into said opening, an intermediate lamp-supporting plate interposed between said lamp socket and said inner annular plate and adapted to form the lamp-supporting sign board or plate of an electric sign, and securing means in screw-threaded engagement with said screw-threaded metallic sleeve portion of said socket and adapted to engage said inner annular plate, and acting to secure said inner annular plate and said lamp socket on opposite sides of and in rigid relation to said intermediate lamp-supporting plate.
3. In a device of the class described, the combination of a glass lamp hood adapted to enclose a lamp bulb, an outer annular flanged metallic hood-engaging member in supporting engagement with said hood, an inner annular metallic supporting plate detachably connected with and adapted to support said outer flanged metallic hood-engaging member, and provided with an opening for receiving a lamp socket, an electric lamp having a lamp socket extending into said opening, an intermediate lamp-supporting plate extending between said lamp socket and said inner annular plate and adapted to form the lamp-supporting sign board of an electric sign, and an annular screw-threaded flanged sleeve in screw-threaded engagement with said socket and adapted to engage said inner annular metallic plate, said screw-threaded sleeve and socket comprising clamping means acting to clamp said socket and said inner annular plate on opposite sides of and in rigid engagement with said lamp-supporting sign board member.
4. In a device of the class described, the combination of a lamp socket adapted to be connected with a lamp bulb of an electric lamp, a metallic outer annular hood-engaging member, means for securing said outer hood-engaging member in supporting engagement with a lamp hood, for enclosing the lamp bulb, an inner annular plate located within said outer hood-engaging and supporting member, means for detachably connecting said inner annular plate in securing engagement with said outer annular hood-engaging and supporting member, a lamp-supporting plate interposed between said lamp socket and said inner annular plate and adapted to form a sign board of an electric sign, and a screw-threaded sleeve having screw-threaded connection with said lamp socket and extending through an opening in said lamp-supporting plate and through and in clamping engagement with said inner annular plate, said connected screw-threaded sleeve and socket comprising means for clamping said inner annular plate and said lamp socket on opposite sides of and in rigid relation to said lamp-supporting plate by turning said sleeve relatively to the connected socket member.

Signed at Chicago, in the county of Cook and State of Illinois, this 29th day of March, 1926.

WILLIAM L. LAIB.
